UNITED STATES PATENT OFFICE.

STUART W. PARSONS, OF NEW BRITAIN, CONNECTICUT, ASSIGNOR TO THE STANLEY WORKS, OF NEW BRITAIN, CONNECTICUT, A CORPORATION OF CONNECTICUT.

DESIGN FOR A DOOR CATCH.

Application filed September 12, 1924. Serial No. 10,761. Term of patent 14 years.

To all whom it may concern:

Be it known that I, STUART W. PARSONS, a citizen of the United States, and a resident of New Britain, in the county of Hartford, State of Connecticut, have invented a new, original, and ornamental Design for a Door Catch, of which the following is a specification, reference being had to the accompanying drawing, forming part hereof.

In the accompanying drawing:

Figure 1 is a top plan view of a door catch showing my design.

Fig. 2 is an end view thereof; and
Fig. 3 is a front view.

I claim:

The ornamental design for a door catch, as shown.

STUART W. PARSONS.
